UNITED STATES PATENT OFFICE.

JOHN C. MILLER, OF COVINGTON, KENTUCKY, ASSIGNOR, BY MESNE ASSIGNMENTS, TO THE H. H. MILLER INDUSTRIES COMPANY, OF CANTON, OHIO, A CORPORATION OF OHIO.

INTERMITTENT DRIVING DEVICE FOR BOTTLE-FEEDING MECHANISM.

1,373,143.

Specification of Letters Patent. Patented Mar. 29, 1921.

Original application filed May 21, 1906, Serial No. 317,918. Divided and this application filed June 13, 1917. Serial No. 174,613.

To all whom it may concern:

Be it known that I, JOHN C. MILLER, a citizen of the United States, residing at Covington, in the county of Kenton and State 5 of Kentucky, have invented certain new and useful Improvements in and Relating to Intermittent Driving Devices for Bottle-Feeding Mechanism, of which the following is a specification.

10 This invention relates to a driving device for bottle feeding mechanism, particularly mechanism for feeding and moving bottles to predetermined positions in apparatus wherein the bottles are washed and sterilized.

The object of the invention is to provide an improved driving device, whereby the bottles are moved through the apparatus and positioned for treatment.

20 Other objects of the invention will be apparent to those skilled in the art to which my invention relates from the following description taken in connection with the accompanying drawings.

25 This application is a division of my application Ser. No. 317,918, Patent No. 1,234,373.

For the purpose of illustration, I have, in the accompanying drawings, shown and herein described one form of apparatus embodying my invention.

30 Figure 1 is a fragmentary transverse sectional view of a bottle washing apparatus having a driving device for the bottle feeding mechanism embodying my invention.

35 Fig. 2 is a fragmentary horizontal sectional view illustrating details of construction.

Figs. 3 and 4 are detail views.

In the drawings, 2 indicates the frame of 40 the apparatus herein shown as adapted for washing and sterilizing empty bottles. 1 indicates a tank for holding water or other cleaning solution. 3 indicates a power driving shaft extending longitudinally of the frame 2 and mounted in suitable bearings at the side thereof. 5 indicates a gear fixed to the shaft 3 and meshing with a gear (not shown) fixed to the shaft of a main gear 97, which, through a train of gears 56, 57, rotates the spindles of a set or sets of scrubbing brushes (not shown).

50 6 indicates a worm fixed to the shaft 3 and meshing with a worm wheel 7 on a trans-

verse shaft 8, which carries suitable cams, whereby movement is imparted to the other 55 elements of the machine.

The bottles to be washed and sterilized are, in the herein illustrated form of construction, placed in an inverted position in suitable cases, racks or trays (hereinafter 60 for convenience termed "racks") for intermittent movement through the apparatus. 9 indicates guideways or tracks mounted on the frame 2 above the washing, rinsing and sterilizing mechanisms. The guideways extend from end to end of the machine and 65 serve to properly guide, support and direct the bottle-carrying racks therethrough.

11 indicates a pair of endless chains which are arranged at opposite sides of the frame 70 2 and form part of the conveying system. The chains 11 preferably extend in a horizontal plane slightly above the guideways 9. The chains 11 are provided with laterally 75 projecting studs 10, which are uniformly spaced thereon. Each chain 11 is supported by and runs around sprocket wheels 49, only two of which are shown, arranged near the opposite ends of the machine. The inner or adjacent runs of the chains 11 are disposed close and parallel to the guideways 80 9 so that the studs will project over the guideways and engage the rear ends of the bottle racks.

Referring to the devices for imparting 85 intermittent movement to the driving chains 11, 33 is a grooved cam fixed to the shaft 8 and arranged to act upon a stud 34 on a swinging yoke 35, which, as shown in Figs. 1, 2 and 3, is pivoted at its lower end preferably to one of the cross bars of the frame 2. 36 is a bar mounted on the yoke 35 so as to be free to slide vertically in the forks thereof. The bar 36 is pivotally connected at its upper end to a transverse slide bar 95 37, which is suitably mounted in and guided by bearings on the opposite side frames of the machine. 38 indicates a link which connects the slide bar to the outer or free end of an arm 39, which in turn is swingably 100 connected at its inner end upon a vertical shaft 40. 41 indicates a pawl carried by the arm 39 for engaging with the teeth of a ratchet wheel 42 secured to said shaft 40.

The shaft 40 is provided with a spur wheel 105 43, which meshes with a spur pinion 44 on

a vertical shaft 45, and said spur wheel 43 also drives, through the medium of an interposed spur wheel 46, a spur pinion 47 on a vertical shaft 48.

5 The shafts 45 and 48 are adapted to suitable bearings in the opposite side frames of the machine, and each of said shafts is provided, at its upper end, with a chain wheel 49, one of these wheels engaging the chain 11 at one side of the machine, and the other engaging the chain 11 at the opposite side of the machine.

128 indicates a steam pipe leading to the sterilizing mechanism, preferably comprising pipes 23 carrying jet nozzles 24, and provided with a self-closing valve 129. To economize on the steam used for this purpose, I prefer to supply steam thereto intermittently in correlation to the feed of the bottle racks. For this purpose, the transverse slide bar 37 is provided, at one end, with a hook 52 which, as the slide is approaching the limit of its movement in the direction of the arrow (Fig. 2) engages with the 20 handle of the valve 129 and opens it for a limited time to permit communication between the steam pipe 127 and the branch pipe 128, thus supplying steam to the sterilizing mechanism, which supply, however, is cut off as soon as the slide bar 37 has completed a predetermined portion of its return movement.

It will be understood that many modifications of the machine can be made without interfering with the general structure and purpose of the same; hence I wish to be understood that my disclosures and the 35 description herein are purely illustrative and are not intended to be in any sense limiting, as widely differing embodiments and

applications of the invention will suggest themselves to those skilled in the art without departing from the spirit and scope thereof.

What I claim is:

45 1. In apparatus of the class described, the combination with a support having guides and a device to be operated, of a pawl and ratchet mechanism, a slide slidably mounted to move endwise in the guides on said support and operatively connected to said pawl, a yoke comprising two relatively movable elements slidable one relative to the other, one of said elements being pivotally connected to said support and the other of 50 said elements being pivotally connected to said slide for operating the latter, and means engaging said first mentioned element for swinging said yoke about the pivotal connection of said first mentioned 55 element on said support.

2. In apparatus of the class described, the combination with a support having guides and a device to be operated, of a pawl and ratchet mechanism, a slide slidably 60 mounted to move endwise in the guides on said support and operatively connected to said pawl, a yoke comprising two relatively movable elements slidable one relative to the other, one of said elements being pivotally 65 connected to said support, and the other of said elements being pivotally connected to said slide for operating the latter, and a cam engaging with said first mentioned element for oscillating said yoke about the 70 pivotal connection of said first mentioned element on said support.

In testimony whereof I have hereunto signed my name.

JOHN C. MILLER.
